SANFORD S. BURR, OF DEDHAM, MASSACHUSETTS.

Letters Patent No. 96,196, dated October 26, 1869.

IMPROVED CABINET-BEDSTEAD.

The Schedule referred to in these Letters Patent and making part of the same.

To all to whom these presents shall come:

Be it known that I, SANFORD S. BURR, of Dedham, in the county of Norfolk, and Commonwealth of Massachusetts, have made an invention of a new and useful Cabinet or Secretary Bedstead; and do hereby declare the following to be a full, clear, and exact description thereof, due reference being had to the accompanying drawings, making part of this specification, and in which—

Figure 1 is a perspective representation of my invention, in an open or extended state, and ready for occupancy;

Figure 2 being a vertical section of the same, in a contracted or closed state.

The purposes of a cabinet or secretary-bedstead, so called, are well known. As their object is to economize room, and enable an apartment to serve the double purpose of a living and a sleeping-room, it naturally happens that the class of persons who purchase them are those who, from necessity or choice, practice domestic retrenchment and economy.

The necessities of a greater portion of this class preclude the possession of an ornamental or expensive article of furniture, and the principal object I have had in view has been mainly to reduce to practical low cost and simplicity an article of furniture which has heretofore been an expensive one, and, secondarily, to reduce the bulk of such articles as compared with others of its class.

In carrying out my present invention, I produce a shell or case, shown at A in the accompanying drawings, which illustrate my invention, such shell or case, upon its exterior, being made in imitation of a cabinet or other analogous article of household-furniture.

A superstructure, of any desired design or purpose, may be added to this cabinet, but whether such superstructure be a book-case, side-board, or other design, it has no connection with this invention, and may be added or not, according to the means or desires of the owner.

In cabinet-bedsteads, as heretofore constructed, so far as my knowledge extends, if any attempt has been made to reduce the length of the bed-bottom, when inserting it within its receiving-shell or structure, such contraction has been effected by dividing such bottom in the centre, or thereabouts, and hinging the two portions endwise together.

This of necessity requires double the depth of space for the reception of the bed-bottom than would be the case were such bottom not divided and folded.

By my construction of the bed-bottom, I obtain the advantage of the reduced height resulting from the folding of the same, without the increase of depth usually ensuing from the doubling of it, and I attain this object by making such bed-bottom in two or more

sections, united by tongued and grooved rails, in such manner as to permit of an endwise contraction of its length, without increase of its depth, the slats being combined with such folding frame by a method which enables them to conform themselves automatically to its varying contractions or expansions.

The bed-bottom, as shown in the accompanying drawings, is composed of two portions, each being a rectangular frame, *a a'*; one of these frames, or the inner one, *a'*, being of less width than its fellow, in order to slide within it.

These horizontal frames are united by an intermediate bar, *b*, provided with longitudinal tongues or splines upon each side, a groove, *c*, being formed in the contiguous face of each side-rail *d* or *d'* of the frames *a a'* to receive these tongues.

This construction and arrangement of the frames *a a'* and grooved bar *b* produce a strong and stiff frame for a bed-bottom, and enables the whole to be expanded or contracted in length, as the case may be.

Furthermore, I dispose upon the upper surface of the frames *a a'*, a series of transverse slats *e e*, &c., and I secure such plurality of slats together by elastic cords *f f*, secured to each, the extremities of these cords being made fast to the head and foot-boards *g h*, which compose the opposite extremities of the frames *a a'*.

I also dispose upon the upper surface of each slat a number of upright coiled-springs, *i i*, &c., such springs, in aggregate, forming an elastic foundation for a mattress, a suitable sacking, *j*, being extended over these springs and from the head to the foot-board of the bed-bottom, and secured in a suitable manner to each.

It will be apparent that by the mode of applying the slats and sacking to two frames *a a'*, that such constituent parts will accommodate themselves automatically to the separation or contraction of such frames.

The inner frame *a'* is hinged at its under part to the lower part of the case of the structure, or to the upper edge of the ledge *k*, forming the lower boundary of the bed-receiving opening of such case, in order to raise the bed-bottom some distance above the floor, the frame *a'* protruding inwardly beyond such ledge to a distance equal to the height of the latter from the floor. As a certain portion of the lower part of the case A must be devoted to the reception of the length of the mattress in excess of that of the bed-bottom in its shortest condition, an aperture would be left between the foot-board and the front boundary of such case when the bed-bottom was in a horizontal position.

In order to cover this aperture at such times, and to prevent sagging of the end of the mattress, I pivot a shelf, *l*, to the interior of the case, and directly over this aperture.

When the bed-bottom is lowered and extended, this

shelf *l* is to be lowered into a horizontal position, as shown in fig. 1 of the drawings, which brings it nearly to a level with the upper ends of the springs *i i*, and enables it to serve as a rest to the end of the mattress.

When about to close the bed-bottom within the case *A*, this shelf should be raised into a vertical position against the front of the structure, as shown in fig. 2 of the drawings, in which condition it is out of the way of the bedding.

As the ledge *k* serves as a support to the inner end of the bed-bottom, we must provide a support also for its opposite end, in order to secure a horizontal position, and this I accomplish by pivoting two legs *m m* within slots *n n'*, made through the outer rail *o* of the frame *a*, or the portion of such rail projecting outwardly beyond the head-board.

The legs, when turned into a position flush with the rail, should fill the slots in order to present a finished appearance, and when turned down into a perpendicular position, shall raise the end of the bed-bottom from the floor, as shown in fig. 1 of the drawings.

Although, in the accompanying drawings, I have represented the case of the structure opening at the front, it may open at the rear, though in practice the former mode will undoubtedly be found preferable.

I would remark that circumstances may render it desirable to cut away a portion of the top of the cabinet, shown at *p* in the drawings, and compel the head-board of the bed bottom to supply the vacancy.

By the above-described arrangement of parts, I am enabled to reduce to a considerable extent the depth of the case *A*, as compared with others of its class, or should I retain the ordinary depth of such case, I can

avoid crowding or squeezing into a small compass of the bed-clothing, as now practiced, and obtain a roomy and ventilated interior to the case.

A cabinet-bedstead made as above described, while enabling me to produce a bed-bottom equally luxurious with the most costly, also enables me to finish the whole device at a very small comparative cost, or sufficiently so to place it within the means of a large class of the population to whom such articles have heretofore been shut out on account of their high cost.

Claims.

I claim—

1. A cabinet or secretary-bedstead, composed of a case or structure, *A*, and a divided bed-frame, which, while hinged to said case so as to be turned bodily up or down upon its pivot, is also capable of longitudinal expansion and contraction, substantially as and for the purpose herein shown and described.

2. A bed-bottom for cabinet or secretary-bedsteads, composed of two end-frames, united by a tongued rail, as explained, or its equivalent, and provided with the transverse slats *e*, secured together by the elastic cords *f*, and provided with the springs *i*, overlaid by the sacking *j*, substantially as and for the purposes herein shown and described.

3. The combination of the pivoted shelf *l* with the hinged and divided bed-frame and the case *A*, in the manner and for the purposes shown and set forth.

SANFORD S. BURR.
